SAFETY LOCK FOR FIREARMS

Application filed February 12, 1930. Serial No. 427,857.

My invention relates generally to auto-loading firearms and has for its purpose the provision of extremely simple means for locking the hammer of a firearm in cocked position during the loading operation so that a release of the hammer as a result of shocks to which the firearm is subjected by the loading operation, will be prevented, thus obviating jamming as well as unintentional discharging of the firearm, and all without the necessity of using a hard trigger pull.

More specifically my invention functions automatically during the use of the firearm, by locking the sear of the latter in cocking engagement with the hammer so long as the trigger is held in its rearmost position, and releasing the sear when the trigger is permitted to move forward to its normal position for actuation to again discharge the firearm.

I will describe only one form of safety lock for firearms embodying my invention and will then point out the novel features thereof in claims.

In the accompanying drawing,

Figure 1 is a fragmentary sectional view of a conventional auto-loading firearm with one form of safety lock embodying my invention, associated therewith;

Figure 2 is a view similar to Figure 1 and illustrating the safety lock functioning to lock the hammer of the firearm in cocked position, and,

Figure 3 is a fragmentary sectional view taken on the line 3-3 of Figure 1 and looking in the direction of the arrows.

Referring specifically to the drawings in which similar reference characters designate similar parts in each of the several views, my invention in its present embodiment is shown associated with a conventional form of firearm in which a hammer 10 is pivoted at 11 in the main frame 12 and is normally urged forwardly by a spring 13 to strike the firing pin 14. A sear 15 is pivoted at 16 in the main frame and is normally urged by a spring 17 into engagement with the hammer so as to enter a cocking notch 18 in the hammer when the latter

is automatically cammed to cocked position in response to rearward movement of a recoil operated slide 19 mounted on the main frame and in which the firing pin 14 is mounted.

The sear 15 is adapted to be actuated to release the hammer and discharge the firearm, by means of a trigger 20 slidably mounted in the main frame and urged forwardly to the normal position shown in Figure 1, by a spring 21 engaging a disconnector 22 slideable vertically in a slot 23 in the sear and in an opening 24 in the frame. The disconnector is provided with lips 25 which normally engage the rear flat end of the trigger under the urging action of the spring 21, and are disposed to engage and rock the sear about its pivot 16 sufficiently for the sear to release the hammer, during the initial rearward movement of the trigger from its normal forward position shown in Figure 1. The disconnector thus normally forms an operative connection between the trigger and sear to cause the latter to release the hammer and discharge the firearm when the trigger is pulled. Upon rearward movement of the slide 19 under the action of the recoil instantaneously following a discharge of the firearm, the disconnector 22, which normally is maintained by the spring 21 in the elevated position shown in Figure 1, so as to dispose its upper end in a cavity 26 in the slide, is cammed downwardly by the slide to disengage its lips 25 from the sear so that the sear is disconnected from the trigger during the remainder of the trigger's rearward movement to its rearmost position shown in Figure 2, and is free to again enter the cocking notch 18 of the hammer upon camming of the latter to its cocked position by the slide.

In firearms of the construction and operation thus far described, which is typical of auto-loading firearms, reliance is placed solely on the sear spring 17 to maintain the sear in cocking engagement with the notch 18 of the hammer. It has been found in practice, however, that the spring 17 is unreliable and that as a result of the shock to which the firearm is subjected by the load-

ing operation, and particularly incident to the sudden checking of the loading or return movement of the slide 19 indicated by the arrow A in Figure 2, the sear is sometimes jarred out of engagement with the notch 18 so that the hammer is released prematurely and unintentionally, to jam or again discharge the firearm.

The safety lock provided by my invention comprises a movably mounted member M in the present instance illustrated as being pivoted intermediate its ends on a pin 27 supported in the main frame 12, to provide portions or arms 28 and 29 on opposite sides of the pin. The arm 28 can be positioned to be either engaged directly by the trigger, or by the disconnector or its spring, and in the present instance is disposed so as to be engaged by the rear flat end of the trigger during the latter part of the trigger's rearward movement to its rearmost position shown in Figure 2. The arm 29, which extends laterally as shown in Figure 3, is disposed to engage and bear against the sear 15 when the arm 28 is moved by the trigger during the latter part of the trigger's rearward movement to the position shown in Figure 2, and to thus supplement the sear spring 17 and positively maintain the sear in cocking engagement with the notch 18 of the hammer so long as the trigger is held in its rearmost position.

It will thus be clear that after the hammer has been released to discharge the fire-arm in response to the initial rearward movement of the trigger from its normal forward position shown in Figure 1, that during the remaining rearward movement of the trigger the latter is automatically disconnected from the sear and the latter then positively prevented by the member M against releasing the hammer from its cocked position until the trigger is released and is returning to its normal forward position.

As it is a practical impossibility to release the trigger from its rearmost position during the loading operation instantaneously following a discharge of the firearm, the member M will thus function automatically to positively lock the sear against releasing the hammer from its cocked position, thereby obviating the jamming or repeated discharging of the firearm unintentionally.

By the provision of my invention, the use of a heavy trigger pull in order to prevent premature release of the hammer by shocks incident to the loading operation, is rendered unnecessary, which is a decided advantage to the shooter, as a moderately light trigger pull is practically essential for accurate shooting.

Although I have herein shown and described only one form of safety lock for fire-arms embodying my invention, it is to be

understood that various changes and modifications may be made therein without departing from the spirit of the invention and the spirit and scope of the appended claims.

I claim:

1. In an auto-loading firearm having a hammer, a sear, and a trigger for releasing the sear from the hammer to discharge the firearm, means for disconnecting the trigger from the sear upon discharge of the firearm so that the sear is free for engagement with the hammer, means for automatically cocking the hammer during the loading operation, and means so controlled by the trigger as to prevent the release of the hammer from cocked position as a result of shocks to which the firearm is subjected by the loading operation.

2. In an auto-loading firearm having a hammer, a sear, and a trigger for releasing the sear from the hammer to discharge the firearm so that the sear is free for engagement with the hammer, means for automatically cocking the hammer during the loading operation, and automatic means for positively locking the hammer in cocked position so long as the trigger is held depressed.

3. In an auto-loading firearm having a hammer, a sear, and a trigger for releasing the sear from the hammer to discharge the firearm, means for disconnecting the trigger from the sear upon discharge of the firearm so that the sear is free for engagement with the hammer, means for automatically cocking the hammer during the loading operation, and means operable by the trigger so long as the latter is held against returning to its normal position, to lock the hammer in cocked position.

4. In an auto-loading firearm having a hammer and releasing mechanism therefor including a sear and a trigger for actuating the sear, means for disconnecting the trigger from the sear upon discharge of the firearm so as to permit the sear to again engage the hammer, means for automatically moving the hammer to cocked position during the loading operation for cocking of the hammer by the sear, and automatic means for positively maintaining the sear in cocking engagement with the hammer so long as the trigger is held against returning to its normal position.

5. In an auto-loading firearm having a hammer and releasing mechanism therefor including a sear and a trigger for actuating the sear, means for disconnecting the trigger from the sear upon discharge of the firearm, so as to permit the sear to again engage the hammer, means for automatically moving the hammer to cocked position during the loading operation for cocking of the hammer by the sear, and means co-acting with

the trigger during the latter part of the trigger's movement to its rearmost position, to positively maintain the sear in cocking engagement with the hammer.

6. In an auto-loading firearm having a hammer and releasing mechanism therefor including a sear and a trigger for actuating the sear, means for disconnecting the trigger from the sear upon discharge of the firearm so as to permit the sear to again engage the hammer, means for automatically moving the hammer to cocked position during the loading operation for cocking of the hammer by the sear, and means operable by the trigger so long as the latter is held in its rearmost position, to positively maintain the sear in cocking engagement with the hammer.

7. In an auto-loading firearm having a hammer and releasing mechanism therefor including a sear and a trigger for actuating the sear, means for disconnecting the trigger from the sear upon discharge of the firearm so as to permit the sear to again engage the hammer, means for automatically moving the hammer to cocked position during the loading operation for cocking of the hammer by the sear, and means movable by the trigger into such engagement with the sear, as to maintain the sear in cocking engagement with the hammer so long as the trigger is held against returning to its normal position.

8. In an auto-loading firearm having a hammer and releasing mechanism therefor including a sear and a trigger for actuating the sear, means for disconnecting the trigger from the sear upon discharge of the firearm, so as to permit the sear to again engage the hammer, means for automatically moving the hammer to cocked position during the loading operation for cocking of the hammer by the sear, and a movably mounted member having portions, one of which is responsive to rearward movement of the trigger to move the other into engagement with the sear and positively maintain the latter in cocking engagement with the hammer so long as the trigger is held in its rearmost position.

9. In an auto-loading firearm having a hammer and releasing mechanism therefor including a sear and a trigger for actuating the sear, means for disconnecting the trigger from the sear upon discharge of the firearm so as to permit the sear to again engage the hammer, means for automatically moving the hammer to cocked position during the loading operation for cocking of the hammer by the sear, and a pivotally mounted member having arms, one of which is responsive to rearward movement of the trigger to move the other into engagement with the sear and positively maintain the latter in cocking engagement with the ham-

mer so long as the trigger is held in its rearmost position.

10. A safety lock for auto-loading firearms comprising a movably mounted member having a pair of portions, one of which is responsive to rearward movement of the trigger of the firearm to move the other into engagement with the sear of the firearm and positively maintain the sear in cocking engagement with the hammer of the firearm so long as the trigger is held in its rearmost position.

11. A safety lock for auto-loading firearms comprising a member having two portions, and means for mounting the member for such movement as to render one of said portions responsive to rearward movement of the firearm's trigger, to move the other of said portions into engagement with the firearm's sear and positively maintain the sear in cocking engagement with the hammer of the firearm so long as the trigger is held in its rearmost position.

12. A firearm having a hammer, a sear, and a trigger for releasing the sear from the hammer, and trigger controlled means co-acting with the sear to lock the hammer in cocked position so long as the trigger is held depressed.

13. Fire control mechanism for firearms comprising a hammer, a sear, and a trigger for releasing the sear from the hammer, a member having portions, and means for mounting the member in a position for one of said portions to respond to rearward movement of the trigger, to move the other portion into such engagement with the sear as to maintain the latter in cocking engagement with the hammer so long as the trigger is held depressed.
